UNITED STATES PATENT OFFICE

WILLIAM J. MERTEN, OF PITTSBURGH, PENNSYLVANIA, ASSIGNOR TO WESTINGHOUSE ELECTRIC & MANUFACTURING COMPANY, A CORPORATION OF PENNSYLVANIA.

SECTIONAL ELECTRIC FURNACE.

Application filed September 20, 1921. Serial No. 502,044.

To all whom it may concern:

Be it known that I, WILLIAM J. MERTEN, a citizen of the United States, and a resident of Pittsburgh, in the county of Allegheny and State of Pennsylvania, have invented a new and useful Improvement in Sectional Electric Furnaces, of which the following is a specification.

My invention relates to heat-treating furnaces and particularly to electrical heat-treating furnaces and it has for one of its objects to provide a furnace of relatively simple construction for electrically heating material passed therethrough and having provisions for varying the active length thereof.

Another object is to provide, adjacent to the furnace chamber, a heat-conserving and material-storing chamber with means located therein for supporting the heated material.

Another object is to provide means located in said storing chamber for moving the material out of said chamber and electrically controlled means for shifting the heated material from the supporting means to the moving means.

In practising my invention, I provide a plurality of walls of any suitable construction usually employed in the art, enclosing an elongated furnace chamber. I provide a plurality of spaced partitions and means for moving one or more thereof to vary the active length of the furnace chamber.

I provide suitable electrical heating elements located in the floor, and in the walls, as well as in the partitions, of the furnace, to permit of uniformly heating the entire active portion of the furnace chamber.

I provide an inlet and an outlet opening in two opposing walls of the furnace and locate a charging platform adjacent to the inlet opening and a heat-conserving and material-storing chamber adjacent to the outlet opening. The floor of the furnace chamber is given a predetermined slope from the charging platform to the material-storing chamber to permit gravity to move the material through the chamber.

I provide suitable means for supporting the heated material in the heat-conserving chamber and further provide means within the said chamber to move the material out of the same, as may be desired. Electrically controlled means are provided, to be governed by the operator, to shift the heated

material from the supporting means to the moving means.

In the single sheet of drawings,

Figure 1 is a top plan view of a furnace embodying my invention;

Fig. 2 is a view, in transverse section, on the line II--II of Fig. 1, and

Fig. 3 is a fragmentary longitudinal section of a portion of the floor of the furnace.

A heat-treating furnace, designated generally by the numeral 10, comprises an elongated furnace chamber defined by end walls 11 and 12, side walls 13 and 14, a floor 15 having an inclined upper surface and a roof 16, all of which are constructed of such bricks or blocks of heat-resisting and heat-insulating material, as are usually employed in the art. While I have illustrated the floor 15 as relatively thick, this is not essential, as it is only necessary that the thickness shall be sufficient to prevent undue loss of heat therethrough. As the round bars to be heat-treated roll on the floor, suitable abrasion-resistant materials are employed in its construction. The inclination of the floor is made a predetermined amount so that the bars will move through the furnace chamber at such rate that their temperature will reach the desired value by the time they have traversed the chamber.

A charging platform 17, located adjacent to the inlet end of the furnace, has a surface inclination or slope corresponding to that of the floor of the furnace in order that cylindrical metal bars to be heat treated may move uniformly into and through the furnace under the action of gravity. An inlet opening 18 in the wall 13 may be equipped with a hinged door 19 of any suitable construction and material to substantially close it as the material to be treated passes therethrough. An outlet opening 20 is provided in the wall 14 to permit the heat-treated material to leave the furnace chamber.

Vertically movable partitions 21 are provided at spaced intervals to permit of varying the active length of the furnace. If relatively short lengths of material are to be heat treated, all of the partition members may be in their lowest positions, while, if longer material is to be heat treated, one or more of the partitions may be raised until, if necessary, the entire length of the furnace chamber, or a plurality of separate portions, may be in active use. The vertical movement

of the partitions may be effected in any desired or suitable manner and is not here illustrated in detail as it forms no part of my invention.

5 Electric heating elements are located in the side and end walls of the furnace chamber and may be of any suitable or desired construction usually employed in furnaces of the above-indicated character. A plurality of resistor members 22, in the form of rods, bars, strands or strips, are located in the floor of the furnace chamber. I have illustrated the construction of the heating element in the floor more particularly in 15 Fig. 3 of the drawing, wherein the resistor members 22 are shown as rods located in the recesses or grooves 23. The ends of the individual resistor members 22 may project outside of the furnace chamber to permit 20 of suitably connecting the members in parallel-circuit or in series-circuit relation with each other.

Electric heating elements 25 are embedded in, or mounted on, each of the surfaces of the partitions 21 and are severally provided with suitable depending contact terminals 26 to engage stationary contact terminals (not shown) when in their normal operative positions.

30 By employing suitably connected control switches (not shown) it is possible to selectively energize any group of resistors in accordance with the operative length of the furnace, as determined by the movable partitions 21 or in accordance with the separate active portions thereof.

A heat-conserving and material-storing chamber 27 is located adjacent the heat-treating furnace 10 at the outlet end thereof 40 and comprises end walls 28, an outer side wall 29 and a roof 31, all of which may be constructed of suitable bricks or blocks of such heat-resisting and heat-insulating material as is usually employed in the art. 45 Partitions 32, located substantially in the same planes as the partitions 21, are provided in the chamber 27 to permit of increasing the active length of the heat-conserving chamber or of dividing the same in 50 accordance with the active length of the heat-treating furnace 10, or its division into separate sections, as hereinbefore described.

A material-supporting means is located in the material-storing chamber 27 and comprises a plurality of laterally extending bars 33 suitably secured to longitudinally extending members (not illustrated) to form a unitary rack.

60 The supporting means is held in its normal operative and raised position by a metal framework 35 controlled by a lever 36 pivotally connected thereto. The lever 36 is maintained in its normal operative position by an electromagnetic device 37, having a 65 winding 38, illustrated only in general in

Fig. 2. The action of the means 37, the pivoted lever 36 and the members 35 is such that, when the winding 38 is energized from a suitable source of electromotive force (not shown) by momentarily closing a circuit, the outer end of the lever 36 is raised to momentarily lower the supporting means 33, which is returned to its normal raised position as soon as the energizing circuit is interrupted.

75 A material-moving means comprises rolls 39 located in laterally spaced relation in the heat-conserving and material-storing chamber 27, which are continuously rotated by a chain 41 which engages sprocket wheels 42 with which the rolls 39 are provided. The entire set of rolls may be continuously operated by means of a suitable driving motor, (not shown) connected to one of the rolls.

80 The operation of the heat-treating furnace is substantially as follows: the furnace being particularly applicable to heating cylindrical metal rods 44 preparatory to being coiled into helical springs or of being otherwise operated upon. A plurality of bars or rods 44 may be placed on the charging platform 17, from which they move into the chamber of the furnace 10 by reason of the slope of the charging platform and continue to move slowly through the furnace chamber at such rate as will result in the temperature of the individual bars reaching the desired value by the time they reach the outlet opening 20. The slope of the floor 15 may be of any suitable degree to permit of obtaining the above described result. When the heated bars pass out through the outlet opening 20 they rest upon the supporting bars 33 which, in their normal elevated positions, maintain the bars out of operative engagement with the continuously rotating rolls 39. When the operator desires to remove one or more of the heated bars from the chamber 27 he momentarily energizes the winding 38, thus lowering the supporting means and causing the heated bar or bars to be engaged by the rotating rolls 39 and be moved thereby out of heat-conserving and material-storing chamber 27 to a place 100 or to a machine for further operation 105 thereon.

110 If it is desired to heat-treat relatively short bars, all of the partitions 21 may be in their lowered positions, and, if it is desired to heat longer bars, one or more of these partitions may be raised to permit of passing the longer bars through the furnace and to permit of heating only so much of the furnace as is required by the lengths of the bars passing therethrough.

115 Various modifications may be made in the device embodying my invention without departing from the spirit and scope thereof, and I desire that only such limitations shall be placed thereon as are imposed by the prior 120 125

art or are specifically set forth in the appended claims.

I claim as my invention:

1. In a heat-treating furnace, in combination, an elongated furnace chamber, means for varying the active length of said chamber, electrical heating elements in the floor and walls of said chamber, and a heat-conserving chamber adjacent to said furnace chamber for storing said heated material.
2. In a heat-treating furnace, in combination, a furnace chamber having an inlet and an outlet for material being treated, electric heating elements in the walls of said chamber, a heat-conserving and material-storing chamber adjacent to said furnace chamber, means in said material-storing chamber for supporting material heated therein, means for moving material out of said storage chamber and electromagnetically controlled means for shifting material from said supporting means to said moving means.
3. In a heat-treating furnace, in combination, a plurality of refractory walls enclosing a furnace chamber having a sloping floor and an inlet and an outlet opening in said walls, electric heating elements embedded in the walls and floor of said chamber, a charging platform adjacent the inlet opening of said chamber, a heat-conserving and material-storage chamber adjacent the outlet

opening of said chamber, means for supporting heated material in said storage chamber, and electromagnetically controlled means for permitting heated material to be moved out of said storage chamber.

4. In a heat-treating furnace, in combination, an elongated furnace chamber, a plurality of spaced movable partitions for varying the active length of said furnace chamber, electric heating elements in the floor and in the walls of said chamber, and electric heating elements located in said partitions and energized only when the said partitions are in their normal operative positions relatively to said furnace chamber.

5. In a heat-treating furnace, in combination, a plurality of walls and a floor enclosing a furnace chamber, electric heating elements in said chamber for heating material passed therethrough, a plurality of spaced movable partitions for varying the active length of said furnace chamber, the floor of said chamber being sloped downwardly to permit of the material being heated to move through said furnace on the floor thereof under the action of gravity.

In testimony whereof, I have hereunto subscribed my name this 17th day of September 1921.

WILLIAM J. MERTEN.
